HOLDER FOR CANDIES OR THE LIKE

Milton Weinman, Chicago, Ill., assignor to Weinman Brothers, Inc., Chicago, Ill., a corporation of Illinois

Application January 12, 1959, Serial No. 54,139

Term of patent 3½ years

(Cl. D58—2)

Fig. 1 is a perspective view of a holder for candies or the like embodying my new design;

Fig. 2 is an elevational view thereof; and

Fig. 3 is a top plan view thereof.

The bottom of the container is planar, and the container is substantially symmetrical about a vertical axis, but for the leaf-like neck ornament.

I claim:

The ornamental design for a holder for candies or the like, substantially as shown and described.
